Primary Examiner—Mitchell Siegel*Assistant Examiner*—Mark Goodwin(74) *Attorney, Agent, or Firm*—William A. Beckman(57) **CLAIM**

The ornamental design for a skid steer loader machine, as shown and described.

DESCRIPTION

FIG. 1 is a front isometric view of a skid steer loader machine, showing our new design;

FIG. 2 is a left side view thereof, wherein the right side view is a mirror image thereof;

FIG. 3 is a top plan view thereof;

FIG. 4 is a front view thereof;

FIG. 5 is a rear view thereof; and,

FIG. 6 is a left side view thereof, shown with the wheels removed, wherein the right side view is a mirror image thereof.

The phantom dashed lines of FIGS. 1–6 represent environmental subject matter and form no part of the claimed design. The bottom view is not shown as it forms no part of the claimed design.
